UNITED STATES PATENT OFFICE.

ADRIANUS ANTHONIE WILTON VAN REEDE, CZN., OF SCHIEDAM, NETHERLANDS.

AXIAL-FLOW TURBINE.

1,205,062.

Specification of Letters Patent. Patented Nov. 14, 1916.

Application filed January 17, 1916. Serial No. 72,564.

To all whom it may concern:

Be it known that I, ADRIANUS ANTHONIE WILTON VAN REEDE, Czn., subject of the Queen of the Netherlands, residing at Schiedam, Netherlands, have invented certain new and useful Improvements in Axial-Flow Turbines; of which the following is a specification.

This invention relates to axial flow turbines of the type having two oppositely running rotors one of which incloses the other and consisting of two symmetrical halves each of which corresponds to a determined direction of rotation.

15 The object of the invention is an improved arrangement for balancing the axial pressure, so as to avoid collar thrust bearings and the like, thus reducing the losses due to friction, and to provide a more reduced and compact form of turbine of the abovementioned type.

20 In a known turbine of the type to which the invention relates the axial pressure is balanced by passing the steam in two opposite flows through the blades, each flow acting on half the number of rows of blades. This way of balancing the axial pressure, however, requires complicated constructions and excludes the possibility of a compact 25 construction, which is one of the objects of this invention.

According to the invention the axial pressure is balanced by providing partition disks in one of the rotors, said disks dividing 30 each of the two symmetrical halves of the rotors into a number of compartments, in each of which the steam acts on two opposite walls, so that there is no resulting axial pressure. These partition disks may be connected 35 to the hub of the inner rotor and be made to fit steamtight in the drum of the outer rotor, but it is preferred to connect the partition disks to the inner wall of the drum of the outer rotor and to make them 40 fit steamtight around the hub of the inner rotor.

45 It will be understood that it is of supreme importance for the good working of the pressure balancing arrangement, that the compartments formed by the partition disks and by the inner wall of the outer rotor drum or the outer surface of the inner rotor hub be practically absolutely steamtight, as any leakage of steam from one of these com-

partments into the adjoining one would 55 cause a difference between the total pressures acting on each of the two opposite walls of said compartment and thus would derogate from the theoretically absolute balancing of the axial pressure. On the other hand, in 60 view of the compact construction aimed at the packing means should take as little space as possible.

According to the invention the packing means comprise simple flat rings of brass or 65 like metal mounted on the hub of the inner rotor, so as to cover with their sides the joints to be packed. Experience has shown that these rings, being pressed onto the joints to be packed by the steam pressure and 70 thus automatically ground in, form a packing which is almost absolutely steamtight.

In connection with the packing by means of flat rings of very small axial dimensions on the one hand, and with the considerably 75 larger axial dimensions of the rotors at the periphery of the blade wheels on the other hand, the central portions of the partition disks and the blade wheels are according to this invention bent inward in the direction 80 of the plane or symmetry of the turbine, whereas the outer portion is bent outward so as to leave sufficient space for the subsequent rows of blades and for the axial gaps, by which the steam is allowed to enter into the 85 balancing compartments. The space thus obtained at the outer side of the central portion of the rotors is used to lodge the bearings, preferably ball bearings, *i. e.*, reckoning from the middle to the ends of the rotors 90 first the bearings between inner and outer rotor and then those between the outer rotor and the casing of the turbine. In this way the bearings are surrounded by dead steam, which is by far preferable as compared to 95 known arrangements, wherein the bearings are exposed directly to live steam.

To avoid direct contact of the live steam with the parts carrying the inner ball-races, (the steam being supplied to the blade 100 wheels by means of a bore or bores in the shaft) according to this invention said bore or bores is or are provided with steam supply pipes having a diameter substantially smaller than the bore or bores, so as 105 to obtain an insulating space between the walls of the steam supply pipes and the shaft.

In reversible turbines, which are running as a rule in one direction, for example, marine turbines, it is sufficient in most cases to provide an insulating space only about 5 the steam supply corresponding to the usual direction of rotation.

As the difference between the pressures in the adjoining compartments of the two rotor-halves is greater than the difference between 10 the pressures in adjoining compartments of the same rotor-half, the packing between adjoining compartments of different rotor-halves should be very effective. According to the invention, a very effective 15 packing in this place is obtained by forming the partition between the two turbine-halves as a double disk, preferably connected to the outer rotor just as the other partition disks and being likewise packed by 20 flat rings covering the joints at the hub of the inner rotor. The compartment inclosed by the double disk is brought into communication with the condenser, so that leakage of steam from one of the turbine halves into 25 the other is practically rendered impossible.

The invention will be described with reference to the annexed drawing which shows, by way of example, a horizontal sectional view of a marine turbine embodying the 30 invention.

In a casing 1 the shaft 3¹ of the symmetrical outer rotor 3 is supported in ball bearings 2, 2. The shaft 3¹ of the outer rotor has a bore containing the shaft 4¹ of the 35 symmetrical inner rotor 4, the shaft 4¹ being supported in ball bearings 5, 5 connected to the outer rotor. The blade rims 6¹ carrying the blades 6 of the outer rotor are connected to the inner surface of the outer rotor drum 40 3; the blade wheels 10 carrying the blades 7 of the inner rotor are connected to the shaft 4¹ of the inner rotor. Rows of blades 6 are arranged to alternate with rows of blades 7, so that flows of steam passing axially 45 through the blades alternately pass blades of either rotor.

Partition disks 8 are connected to the inner surface of the outer rotor drum 3 and divide each of the symmetrical halves of the 50 outer rotor into three balancing compartments.

As shown in the drawing a wide axial gap 23 is left open in every compartment between the last row of blades in said compartment and the next partition disk, said gap allowing steam to enter into the balancing compartments. Holes 9 are provided in the blade wheels 10 in each compartment so as to allow the steam in such compartments to influence equally both side-walls 8. The pressures on opposite side-walls of each compartment being equal, there is no resulting pressure in either direction.

The packing of the partition disks at their 65 inner edges, around the hub of the inner

rotor, is effected by means of flat rings 22 of brass or like comparatively soft metal, mounted so as to cover the joints between the hubs and the disks 8.

The central portions of the partition disks 70 8 and of the blade wheels 10 are bent inward in the direction of the plane of symmetry of the rotors, whereas these disks and wheels at their periphery are bent outward so as to leave sufficient space for the blades 6 or 7 and the axial gaps 23 at the end of each balancing compartment. The space thus obtained at the outer side of each rotor-half is used for lodging the bearings 5, 5 supporting the inner rotor in the outer 75 rotor and the bearings 2, 2 supporting the outer rotor in the casing 1.

Steam may be supplied to the left half of the rotors (for going ahead, in the case of a marine turbine) by means of a pipe 15, 85 placed in a bore of the shaft 4¹ of the inner rotor and having an outer diameter substantially smaller than the said bore, so that an annular space 11 which is left between the steam supply pipe and the shaft 4 forms 90 an effective heat insulation for the ball bearing 5.

When steam is supplied by the inlet 12 to the annular conduit 11 instead of by the inlet 16, the right half of the turbine is started, the blades 6, 7 of said half being bent so as to cause a rotation of the rotors in a direction opposite to that caused by the blades 6, 7 of the left half. As the right half of the marine turbine shown in the drawing is designed as an astern turbine and, as such, is only set to work exceptionally, no means are provided in this case to insulate the bearing 5 from the supply of live steam. If required, however, the inner supply pipe 15 may be surrounded by a second pipe, serving as supply conduit for the right half of the turbine and the outer diameter of this second pipe may be chosen so as to leave an insulating space between 100 110 said pipe and the shaft of the inner rotor.

In the drawing, the steam supplied by the pipe 15 to the left half or by the annular conduit 11 to the right half of the turbine passes through radial conduits 13 formed in the inner end walls of the halves of the inner rotor 4 to nozzles 14, from which the steam is directed to the alternating rows of blades 6, 7, either of the left or of the right half turbine. After having passed through 115 all the rows of blades the steam reaches the exhaust 18 through holes 17 in the end walls of the outer rotor.

The two halves of the rotors are separated by a double partition disk 19 connected to the inner surface of the outer rotor and enclosing a compartment 20 which communicates with the exhaust 18 by holes 21 in the drum 3 of the outer rotor. At its inner edge 125 the double disk 19 is also packed by flat 130

rings 22, covering the joints between the said disk and the hub of the inner rotor.

What I claim as my invention and desire to secure by Letters Patent is:—

5. 1. An axial flow turbine comprising two symmetrical halves and two oppositely running rotors, partition disks in each of the symmetrical halves adapted to divide each half into a plurality of balancing compartments, and connected to one rotor and making a steamtight joint with the other rotor.

10. 2. An axial flow turbine comprising two symmetrical halves and two oppositely running rotors, partition disks in each of the symmetrical halves adapted to divide each half into a plurality of balancing compartments, and connected to the inner surface of the outer rotor-drum, and a packing comprising flat rings of soft metal extending 15 across the joints between the inner edges of the partition disks and the hub of the inner rotor.

15. 3. An axial flow turbine comprising two symmetrical halves and two oppositely running rotors, partition disks dished inwardly toward the plane of symmetry connected to one motor and making a steamtight joint with the other rotor, and blade wheels disposed between the said disks and similarly 20 dished.

25. 4. An axial flow turbine comprising two symmetrical halves and two oppositely running rotors, partition disks dished inwardly toward the plane of symmetry, connected to one rotor and making a steamtight joint with the other rotor, blade wheels disposed 30 between the said disks and similarly dished.

between the said disks and similarly dished and a packing comprising flat rings of soft metal extending across the joints between the inner edges of the partition disks and the 40 hub of the inner rotor.

5. An axial flow turbine comprising two symmetrical halves and two oppositely running rotors, partition disks dished inwardly toward the plane of symmetry, connected to 45 one rotor and making a steamtight joint with the other rotor, blade wheels disposed between the said disks and similarly dished, and ball-bearings in the central spaces provided by the dishing of said disks and blade-wheels.

6. An axial flow turbine comprising two symmetrical halves and two oppositely running rotors, partition disks dished inwardly toward the plane of symmetry, connected 55 to one rotor and making a steamtight joint with the other rotor, hollow shafts carrying the rotors, steam supply pipes within said shafts having an annular insulating space between them and the walls of the 60 shafts, and blade wheels disposed between the said disks and similarly dished.

7. An axial flow turbine comprising two symmetrical halves and two oppositely running rotors, partition disks in each of the 65 symmetrical halves, and a double partition disk centrally arranged between the two halves, and inclosing a space communicating with the exhaust.

In testimony whereof I have hereunto set 70 my hand.

ADRIANUS ANTHONIE WILTON VAN REEDE, Czn.
